US0D1078273S

(12) United States Design Patent (10) Patent No.: US D1,078,273 S
(45) Date of Patent: * Jun. 10, 2025

(54) LUGGAGE SUITCASE

(71) Applicant: Xiamen Worthfind Co., Ltd., Fujian (CN)

(72) Inventor: Jiasong Li, Fujian (CN)

(73) Assignee: Xiamen Worthfind Co., Ltd., Fujian (CN)

() Term: 15 Years

(21) Appl. No.: 29/914,835

(22) Filed: Oct. 23, 2023

(30) Foreign Application Priority Data

Sep. 21, 2023 (CN) 202330616981.2

(51) LOC (15) Cl. 03-01

(52) U.S. Cl.

USPC D3/321; D3/279

(57) CLAIM

The ornamental design for a luggage suitcase, as shown and described.

DESCRIPTION

FIG. 1 is a front elevational view of a luggage suitcase showing my new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof; and,

FIG. 8 is a second perspective view thereof.

The broken lines shown in the drawings are for the purpose of illustrating portions of the luggage suitcase that form no part of the claimed design.

1 Claim, 8 Drawing Sheets
